MOTORIZED SURFBOARD OR THE LIKE

David J. Levinson, Tarzana, Calif., assignor to
Alfred S. Bloomingdale

Filed June 24, 1965, Ser. No. 85,882

Term of patent 14 years

(Cl. D71—1)

FIGURE 1 is a perspective view taken from the upper rear quarter of a motorized surfboard or the like showing a first species of my new design;

FIGURE 2 is a bottom view thereof;

FIGURE 3 is a left side elevational view thereof;

FIGURE 4 is a plan view thereof; and

FIGURE 5 is a rear elevational view thereof.

FIGURE 6 is a bottom view of a motorized surfboard or the like showing a second species of my new design; and

FIGURE 7 is a perspective view thereof taken from an upper rear quarter.

The view of FIGURE 5 is common to both species.

The dominant features of my design reside in the portions shown in full lines.

I claim:

The ornamental design for a motorized surfboard or the like, substantially as shown and described.
